UNITED STATES PATENT OFFICE.

LEE C. MENSCH, OF MASON CITY, IOWA.

COMPOSITION RAILWAY-TIE AND RAIL-CLAMP.

No. 927,666.

Specification of Letters Patent.

Patented July 13, 1909.

Application filed October 20, 1908. Serial No. 459,269.

To all whom it may concern:

Be it known that I, LEE C. MENSCH, a citizen of the United States, residing at Mason City, in the county of Cerro Gordo and State 5 of Iowa, have invented a new and useful Composition Railway-Tie and Rail-Clamp, of which the following is a specification.

The object of my invention is to form in a suitable mold a composition railway tie and 10 permanently combining metal railway chairs for fastening track rails thereon by detachable metal clamps and keys.

My invention consists in a skeleton metal frame composed of rods and rail chairs im- 15 bedded in concrete ties and metal clamps and keys as hereinafter set forth, pointed out in my claims and illustrated in the accom- panying drawings in which:

Figure 1 is a side view and Fig. 2 a trans- 20 verse sectional view of one of my metal railway chairs. Fig. 3 shows two chairs com- bined with two rods as required to produce a skeleton metal frame adapted to be em- bedded in concrete to produce a complete 25 railway tie. Fig. 4 shows one end portion of a tie in section and a section of a track rail fixed thereon by means of a clamp and key as required for practical use. It also shows a plurality of rods embedded in the concrete 30 to reinforce the concrete tie. Fig. 5 is a transverse section of a tie and chair and apertures in the concrete to admit the pas- 35 sage of a key into the chair as required for engaging a clamp in the chair for binding a track rail on the chair.

The numeral 10 designates the body portion of one of my metal chairs. It has flanges 12 at its sides to aid in securely retaining it embedded in concrete as shown in 40 Fig. 5. Metal rods 13 extend into the sockets in the flanges 12 and a metal rod 14 ex- tends through transverse apertures 15 in the lower ends of the chairs.

Metal clamps 16 of V-shape are placed in 45 the open tops of the chairs, as shown in Fig. 4, as required for engaging the flanges of a

track rail and a metal key, 17, is passed through apertures 18 in the concrete to en- gage the lower end of the V-shaped clamp, 16, as required to draw downward so that 50 the lateral extensions *a* that rest upon the flanges *b* of the track rail as shown in Fig. 4 will bind the track rail, the clamp 16, the chair, 10, and the skeleton frame embedded in the concrete tie, all securely together. 55

Having thus set forth the purposes of my invention and the construction, arrangement and combination of all the parts, the practi- 60 cal operation and utility thereof will be ob- vious.

What I claim as new and desire to secure by Letters-Patent, is:

1. A metal railway chair having flanges at the top, sockets in the flanges to admit rods, an opening in its top to admit a V-shaped 65 clamp and a V-shaped clamp fitted in said opening, to operate as set forth.

2. In a concrete railway tie a metal rail- 70 way chair having flanges at its top, sockets in said flanges to admit rods, rods extended into said sockets, an opening in its top to ad- mit a V-shaped clamp, a V-shaped clamp fitted in said opening, apertures in the side of 75 the tie and a metal key to enter said aper- tures to engage the V-shaped clamp, ar- ranged and combined to operate in the man- ner set forth.

3. A composition railway tie comprising a metal skeleton frame composed of two metal railway chairs and two metal rods, V-shaped 80 clamps in the tops of the chairs, the skeleton frame embedded in concrete as shown, metal V-shaped clamps in the metal chairs and metal keys extended through apertures in the concrete and apertures in the chairs to 85 engage and operate the clamps as set forth for the purposes stated.

LEE C. MENSCH.
